UNITED STATES PATENT OFFICE.

EDMUND TOWNSEND, OF OAK GROVE, ASSIGNOR OF ONE-HALF TO
B. W. COOK, OF NORTHLAKE, MICHIGAN.

GATE.

SPECIFICATION forming part of Letters Patent No. 364,193, dated May 31, 1887.

Application filed October 28, 1886. Serial No. 217,441. (No model.)

To all whom it may concern:

Be it known that I, EDMUND TOWNSEND, a citizen of the United States of America, residing at Oak Grove, in the county of Livingston and State of Michigan, have invented a certain new and useful Improvement in Gates, of which the following is a specification, reference being had therein to the accompanying drawings.

10 This invention pertains to a certain new and useful improvement in gates; and it consists in the detailed construction, combination, and arrangement of the parts, substantially as hereinafter fully set forth, and particularly pointed out in the claim.

15 In the accompanying drawings, Figure 1 is a view in side elevation of my invention, and Fig. 2 is a detail thereof.

20 In carrying out my invention I employ an upright post or standard, A, which is firmly embedded in the earth at its lower end, and the extreme upper end of said post or standard is sharp-pointed or tapered, as at a, the purpose of which will appear farther on. To 25 this post or standard are secured, near either end thereof, two horizontally-disposed plates, a' a', said plates having corresponding apertures for reception of two lugs or projections, b b, formed on the upper and lower ends of a 30 hinging bar, B. By thus securing the ends of said bar the same is permitted to turn or swing, of which more hereinafter.

35 C is a swinging gate, composed of the ordinary horizontal bars, connected at their ends and central portions by suitable upright pieces, and between the two end uprights, b' b', are secured two rolls, b², the same being permitted to turn freely between said uprights. Immediately above each of said rolls b² are secured, 40 between said uprights, two forwardly-projecting arms, d" d", which extend a short distance out beyond this end of the gate, and each two of said arms have secured between their extreme outer ends small rolls or wheels d' d'. 45 These rolls or wheels are disposed sufficiently far from the end of the gate to permit of the passage of the swinging bar B between the rolls b² and d", said rolls bearing, respectively, on the outer and inner vertical edges of said bar, the 50 latter for this purpose being slightly rounded.

A series of holes or apertures, d², is formed in the hinging bar B, and a correspondingly-shaped aperture, d³, is formed in the lower forwardly-projecting arms, d" d", and from this it will be seen that by inserting an ordinary pin 55 through the aperture formed in said arms and a corresponding aperture in the bar B the gate can be held at any desired point of elevation, the raising of said gate being effected by means now to be described.

60 D are two upright arms pivoted at their lower ends to the central upright pieces of the gate C, said arms projecting above said gate about half their length. Between the upper ends of these arms is pivotally secured 65 one end of a lever, E, said lever being fulcrumed on the upper tapered end of the post A, which end of the post enters a correspondingly-shaped recess or aperture in the under side of said lever.

70 The gate is of course provided on its outer end with the usual sliding latch, f, entering a long slot or aperture formed in the retaining-post F. From this it will be seen that by pulling downwardly on the outer end of the lever 75 E the gate C will be raised or lowered to any desired point, the rolls b² and d² sliding on the swinging bar B. By inserting the pin through the aperture in the lower arms, d", and a corresponding aperture in the bar B, the gate will 80 be retained in this position, and by withdrawing the sliding latch f the gate can be swung in either lateral direction.

85 My gate is so constructed as to provide against sagging of either end thereof; and it will be observed that in the accomplishment of the result stated I dispense with the use of all weights, and my invention is simple, cheap, and durable, and is not liable to get out of order.

90 I am aware that there is no novelty in a farm-gate with oppositely-disposed rolls bearing against the sides of a pivoted bar, in a gate having a perforated pintle for securing the same at any desired height by means of a pin, nor in a gate hinged by means of a long pintle and 95 having a weighted lever fulcrumed on a post and secured to the upper ends of two suspending arms pivoted to the gate; and hence I do not make broad claim to the features here acknowledged to be old.

Having thus fully described my invention, what I claim, and desire to secure by Letters Patent, is—

The combination, with the gate, the post, 5 the lever, and the arms connecting said lever to the gate, of the swinging bar having a series of apertures secured by horizontally-disposed plates projecting from said post, the rolls secured between the end uprights of said gate,

and the forwardly-projecting arms carrying 10 rolls, one pair of said arms being apertured, substantially as shown and described.

In testimony whereof I affix my signature in presence of two witnesses.

EDMUND TOWNSEND.
